(57) **CLAIM**

The ornamental design for a modular shelter as shown and described.

DESCRIPTION

FIG. 1 is a front, right, perspective view in accordance with a first embodiment of a modular shelter showing our new design;

FIG. 2 is a rear, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right, perspective view in accordance with a second embodiment of a modular shelter;

FIG. 10 is a rear and left, perspective view thereof;

FIG. 11 is a cross-sectional view thereof; taken about line 11-11 of FIG. 9;

FIG. 12 is a top plan view thereof;

FIG. 13 is a right-side elevational view in accordance with a third embodiment of a modular shelter; with the left side being a mirror image;

FIG. 14 is a top plan view thereof with the modular shelter shown in another condition of use, with the partitional elements in alternate positions;

FIG. 15 is a right side elevational view thereof; with the left side being a mirror image thereof;

FIG. 16 is a top plan view in accordance with a fourth embodiment of a modular shelter; and,

FIG. 17 is a right-side elevational view thereof, the left side being a mirror image thereof.

The broken lines represent environmental structure which forms no part of the claimed design.

1 Claim, 15 Drawing Sheets
